UNITED STATES PATENT OFFICE.

ANDREW E. MARKWELL, OF FORT WORTH, TEXAS, ASSIGNEE OF ONE-HALF TO
S. C. EVANS, OF FORT WORTH, TEXAS.

RULING TYPE-FORM AND METHOD OF PRODUCING THE SAME.

1,263,335.

Specification of Letters Patent. Patented Apr. 16, 1918.

Application filed December 22, 1917. Serial No. 263,373.

To all whom it may concern:

Be it known that I, ANDREW E. MARKWELL, a citizen of the United States of America, residing at Fort Worth, in the county of Tarrant and State of Texas, have invented certain new and useful Improvements in Ruling Type-Forms and Methods of Producing the Same, of which the following is a specification.

My invention relates to type forms and slugs and rules therefor and also to a method of securing the rules and slugs together in type forms; and the object is to provide simple slugs and rules which will be automatically locked in operative position during the planing operation. One of the objects is to provide rules which will be self-locking. The various lugs or projections on slugs for holding the rules in place are dispensed with and the various matrix molding devices for moldings slugs with such projections are dispensed with and much expense is avoided. Other objects and advantages will be fully explained in the following description and the invention will be more particularly pointed out in the claims.

Reference is had to the accompanying drawings which form a part of this application.

Figure 1 is a perspective view of a type form constructed in accordance with my invention. Fig. 2 is a perspective view, showing the method of fastening the rules and slugs together, three rules being shown in section and placed in the grooves in the slugs above the quad line with their printing edges extending sufficiently above the level top surface of the printing characters, so that when planed or pounded down into the slot the bottom edges of the rule will undercut into the metal, and three rules being shown in section after they have been pressed down in the grooves and the edges of the rules pressed into the metal of the slugs. Fig. 3 is a perspective view of a slug, showing a groove for receiving a rule. Fig. 4 shows a broken slug with leader line thereon, a groove for receiving and holding a rule. Fig. 5 is a broken perspective view of a blank slug with projections thereon for holding the rule in place when the rule has been planed or pounded down level with

printing surface of the type-form and is intended for wide spacing of figure columns. 55

Similar characters of reference are used to indicate the same parts throughout the several views.

The drawings show the improved rules in enlarged views and rules for different 60 purposes are shown. Self-locking rules are provided for all kinds of tabulated and ruled blank forms or blank work. Slugs 1 of standard equipment size are provided, and these slugs have rectangular grooves 2 65 across the slugs to receive the rules, the grooves extending from the quad base upwardly. Rules 3, 4, and 5 are shown in the type-form in Fig. 1. The grooves 2 are made between the type as shown in Fig. 1 and Fig. 3 and through the longitudinal rib for leaders and horizontal ruled lines, as shown in Fig. 4, or through any other projection on a slug above the quad line. A blank slug may be provided with upstanding 70 projections 6, as shown in Fig. 5, for holding the rules in place in widely spaced columns to start the acuated edges 7 down into the metal as hereinafter described. 75

The slug shown in Fig. 2 is for illustration of the method of fastening the rules and not for illustration of type or printing characters. Rule 3 is for the light vertical line printing. Rule 4 is for heavy vertical line printing, and rule 5 is for the double 85 vertical line printing. The three rules are bifurcated in the base and the bifurcation is so made that the two bottom edges are acuated and slightly curved outward. The three rules to the left of Fig. 2 are just lying loose 90 in the grooves 2 and attention is called to the fact they project above the type level and remain in this position until the type and rule is planed or pounded down. When the planer is placed on the type and hammered down, the sharpened or acuated edges of the rules will be pressed downward and spread laterally into the metal of the slugs and the three rules to the right side of Fig. 2 show how the acuated edges 7 of the rules have been pressed downward and laterally 95 into the metal and the top of the rules are brought to the type level. When the edges of the rule are forced down into the metal, they will be curved as shown on the right 100 side of Fig. 2. The rules are thus automati-

- ically locked in the slugs and need no other fastening device, because the rules are securely locked when they are planed or hammered down.
5. What I claim, is,
1. A type-form including slugs and ruling members, said ruling members having a printing edge and acuated base edges which are adapted to penetrate the metal of the 10 supporting slug and to be spread as they are driven into the type of the slug for anchoring the rules to the slug.
  2. A metal printing rule for type forms having the base edges of the rule acuated 15 and adapted to penetrate the metal of the slug and to be flared as they are planed into the metal of the slugs of the type form for self locking of the rule to the slug.
  3. A metal printing rule for type forms 20 having the base edges thereof adapted to be spread and driven into the metal of the slug of the type form below the quad line thereof when the rule is planed down.
  4. A type-form provided with ruling 25 members, each ruling member lying on the quad base of the supporting slugs between the type thereof and having a bifurcated base the edges of which are adapted to penetrate the metal and to be flared as they are 30 planed, into the metal of the slugs for locking the slugs and rules into a type-form.
  5. A type-form composed of slugs having transverse grooves extending down to the quad lines and ruling members placed 35 in said grooves and having bifurcated bases the edges of which are acuated and adapted to penetrate the metal of the slug and to be spread as they are planed into the metal of the slugs for anchoring the ruling member to the slug.
  6. A metal printing rule for type-forms to be placed on the quad line of printing slugs and having a bifurcated base the edges of which are acuated and adapted to spread 45 and undercut their way into the metal of the slug when planed down on the slug for automatically locking the rule to the slugs.
  7. A type-form composed of slugs of type metal and printing rules of harder metal 50 placed on the quad line of the slugs and having a base provided with acuated edges adapted to spread and penetrate their way into the metal of the slugs when the rules are planed down.
  8. A type-form composed of slugs provided with printing characters and transverse grooves between said characters and ruling members placed in said grooves and having acuated edges adapted when planed down to undercut their way into the metal 60 of the slugs for locking the ruling members and the slugs into a type-form.
  9. A type-form composed of slugs having level top surfaces and printing characters rising from said surfaces and transverse 65 grooves between said characters extending to the quad line and ruling members placed in said grooves and provided with acuated edges adapted to cut into said slugs, said edges being adapted to be curved in the metal of 70 the slugs below the quad line thereof.
  10. The herein described method of forming a type-form which consists in placing printing rules across printing slugs and planing the rules down until the printing 75 edges of the rules are on a level with the type level of the slugs and simultaneously forcing the edges of the rules to undercut their way into the metal of the slugs for anchoring the rules to the slugs.
  11. The herein described method of preparing a type-form which consists in assembling slugs and ruling members across the slugs and locking the rules to the slugs by forcing portions of the rules to cut their way 80 into the metal of the slugs for anchoring the ruling members to the slugs.
  12. The herein described method of preparing type-forms which consists in assembling prepared slugs and prepared ruling 90 members across the slugs and planing the slugs and ruling members and forcing portions of the metal of the ruling members to cut their way into the metal of the slugs.
  13. The herein described method of preparing type-forms which consists in assembling prepared slugs having transverse grooves therein and prepared ruling members in said grooves with the tops of the rules higher than the printing characters, 100 planing the ruling members to the level of the printing characters and simultaneously forcing portions of the ruling members into the metal of the slugs.
- In testimony whereof I set my hand, this seventeenth day of December, 1917.
- ANDREW E. MARKWELL.
